CIGARETTE PACKAGE AND MATCHBOOK CONTAINER

Dale D. Hayes, Greensboro, N. C., assignor of one-half to Paul L. Shadburn, Greensboro, N. C.

Application January 22, 1951, Serial No. 207,177

2 Claims. (Cl. 206—38)

1

This invention relates to a package and more especially to a package or container adapted to receive a package of cigarettes and to hold the same for ready dispensation and having in combination therewith means for securing a conventional book of matches to the container so that the book of matches will secure the package of cigarettes within the container to permit withdrawal of individual cigarettes therefrom and wherein the matches will be so positioned that they are available for striking and yet protected from accidental ignition.

It is an object of this invention to provide a cigarette package container which may be formed of plastic or any suitable material and which may be molded as an integral piece or formed by cutting or stamping and assembling the various parts thereof in a very economical manner to provide a rectangular case adapted to receive a package of cigarettes and this case being provided with means for securing a book of matches therein whereby said book of matches may be so positioned as to hold the package of cigarettes within the container.

It is another object of this invention to provide a cigarette package container of the type described which is rectangular in shape and which is provided with an open end which is adapted to receive a package of cigarettes and which has means on one wall thereof for holding a book of paper matches and protecting the heads of said matches whereby the cover of the match book may be extended over the open ends of the cigarette package container and the package container also being provided with means on the other side thereof for frictionally holding the cover of the match book to secure the same in position for holding the cigarette package within the container.

It is another object of this invention to provide a cigarette package container and match book holder in combination wherein the matches will always be available with the cigarettes and wherein the matches are so positioned as to be available for striking but with the match heads protected and wherein any conventional book matches may be used and the cigarettes are locked in the container by the match book cover.

It is still another object of this invention to provide a cigarette container and match book holder of the type described wherein the match book cover confines the cigarette package within the container but permits the individual cigarettes to be withdrawn from the container and said container having no moving parts so that the motions of opening and closing a match book and

2

opening and closing a container are eliminated thus providing a more efficient cigarette package container.

Some of the objects of the invention having been stated, other objects will appear as the description proceeds when taken in connection with the accompanying drawings, in which—

Figure 1 is a front isometric view of the cigarette package and match book container showing the same with a package of cigarettes and a package of book matches therein;

Figure 2 is a rear isometric view of the container and showing the manner in which the cover of the match book is held in position;

Figure 3 is a rear elevation of the container with the cigarette package and match book omitted therefrom;

Figure 4 is a sectional plan view looking down along the line 4—4 in Figure 1 and showing the manner in which the cover is formed for protecting the heads of the matches and omitting the cigarettes and matches;

Figure 5 is a sectional plan view looking down along the line 5—5 in Figure 1 and showing the manner in which the match book retaining member is positioned on the front of the cigarette package container and omitting the cigarettes and matches;

Figure 6 is a vertical sectional view taken substantially along the line 6—6 in Figure 1;

Figure 7 is a fragmentary sectional view looking substantially along the line 7—7 in Figure 3 and showing the manner in which the pressure bar acts to hold the match book cover in position.

Referring more specifically to the drawings, the cigarette package and match book container comprises a substantially rectangular casing having a front wall 10, a rear wall 11, end walls 12 and 13, and a bottom wall 14 all secured together in any suitable manner as by adhesive or formed integral with each other as by molding. The internal dimensions of the casing thus formed are of substantially the same dimensions as the external dimensions of a package of cigarettes or slightly larger so that a package of cigarettes may be positioned in the casing and will fit snugly therein. In the present illustration, the casing is shown as being of a size adapted to receive an ordinary size package of cigarettes but if desired, the casing can be larger in order to receive a package of cigarettes of the longer or "king size" type.

The cigarette package container and match book holder may be formed of any suitable material such as plastic and is preferably molded as an integral unit as illustrated but which may be

formed by cutting or stamping and assembling the various parts thereof.

The upper edges of the end walls 12 and 13 are cut away as at 15 and 16 to permit access to a package of cigarettes such as indicated at P positioned in the casing, containing a plurality of cigarettes C. The casing thus formed may be of any suitable material such as cardboard or plastic or metal and is preferably of a material of sufficient stiffness to prevent the package of cigarettes positioned therein from being crushed.

Now, it is well known that in using cigarettes one must have means for lighting the same and it is usually necessary to carry a lighter or to carry a book of paper matches. To facilitate this and to insure that matches will always be available with the cigarettes, it is an object of this invention to provide means with the casing just described for holding a book of paper matches. Heretofore, various means have been provided for securing a book of paper matches to a cigarette container but in such instances, the matches have been retained in a closed or covered position where it was necessary to open the same before striking the match to light the cigarette since matches left in an open or uncovered position are dangerous. To overcome this, there is provided means associated with the casing just described for holding a book of matches so that the cover thereof may be reversely folded over the casing to assist in securing the cigarette package within the casing and the heads thereof are disposed beneath a cover affixed to or integral with the casing so that they will be protected but which cover will permit the matches to be withdrawn without removing the match book from the casing.

To this end, the upper front wall 10 of the casing is provided with a cover having a top portion 20 and a front wall 21 and diverging side walls 22 and 23 which extend inwardly toward the front wall 10 of the casing and are secured thereto as at 24 and 25, respectively, or which are preferably molded integral therewith. The inner edges of the top 20 of the cover stops short of the front wall 10 of the casing to provide a slot 26 through which a cover 30 of a conventional book of paper matches broadly designated at 31 may be positioned. The match book 31 also includes a plurality of matches 32 secured therein and having heads 33 on the upper ends thereof and a striking surface 34.

In order to retain the match book 31 on the front wall 10 of the casing, there is provided a retaining arm 35 extending across the wall 10 of the casing and secured at each end thereof to the wall 10 or formed integral therewith and which is provided with a slot 36 on the side thereof adjacent the wall 10 to permit the cover 30 of the match book 31 to be positioned in the slot 36 with the retaining member 35 extending between the cover 30 and the matches 32 of the match book 31. The lower front edge of the retaining member 35 is beveled as at 37 to facilitate the insertion of the match book 31 so that as the cover 30 is slid upwardly through the slots 36 and 26, the heads of the matches will easily slide over the beveled portion 37 of the retaining arm 35 and then will be positioned under the top 20 of the cover so that the match heads will be protected. It will thus be observed that an operator may remove one of the matches 32 while the match book is in this position without moving the match book out of position.

Now, to further assist in holding the match

book 31 in position, the rear wall 11 of the casing is provided with a pressure bar 40 extending across the same adjacent the upper edge thereof and which pressure bar 40 is provided with a cut away portion on the side thereof adjacent the wall 11 forming a slot 41 through which the cover 30 of the match book 31 extends. It will be observed in Figures 2 and 3 that the rear wall 11 of the casing is also provided with an opening 42 to permit access to the package C within the housing to facilitate removal of the same and that portion of the pressure bar 40 extending across the opening 42 is provided with a pressure block 43 on the side thereof adjacent the opening 42.

Referring to Figure 7, there will be observed the preferred form of pressure block 43 and it will be noted that the proximate edge of the block 43 and the wall 11 are in substantial alinement so that as the cover 30 of the match book 31 is positioned in the slot 41 the pressure block 43 will serve to distend the cover 30 slightly and frictionally engage the same to hold it securely in position. The pressure block 43 is preferably molded integral with the pressure bar 40 or it may be secured thereto in any suitable manner and it will be observed in Figure 6 that the upper edge thereof is beveled as at 44 to facilitate the insertion of the cover 30 between the same and the wall 11.

The pressure block 43 may be varied in width or thickness, as desired, to vary the amount of friction which will be exerted against the match book cover 30 positioned in the block 41.

By using a cigarette package container of this type, advertising matter may be printed on the inner surface of the match book cover 30 so that it will be exposed to view when the match book is positioned as shown.

It is thus seen that there is provided a casing or container adapted to receive a package of cigarettes and provided with a retaining bar on one wall thereof adapted to have a match book positioned with the cover thereof between the retaining bar and the casing and the matches thereof on the other side of the retaining bar and the casing also being provided with a cover member adapted to cover and protect the heads of the matches thus positioned and said cover member having a slot therein between the same and the wall of the casing to permit the cover of the match book to extend therethrough and over the top of the package of cigarettes positioned in the container to hold the cigarettes in the container and the cover of the match book then extending downwardly between the rear wall of the container and a pressure bar fixed to the container and having a pressure block thereon adapted to frictionally engage the cover of the match book to hold the same securely in position so that an operator may remove cigarettes and matches without disturbing the position of the match book of the cigarette package and without having to open the match book each time a match is desired.

In the drawings and specification, there has been set forth a preferred embodiment of the invention and although specific terms are employed, they are used in a generic and descriptive sense only and not for purposes of limitation, the scope of the invention being defined in the claims.

I claim:

1. A cigarette package and match book container comprising an open ended rectangular cas-

front wall being provided with a retaining bar thereon spaced from the open end of the casing, a match head cover secured to said front wall adjacent the open end of the casing and having a slot therein adjacent said front wall, whereby a match book having a cover may be positioned with its cover between the retaining member and the front wall of the casing and extending through the slot in the match head cover and over the open top of the casing and said casing having a pressure bar on the rear wall thereof having a pressure block thereon adapted to frictionally engage the match book cover to hold the same in position.

2. A cigarette package and match book holder having front, rear and side walls and a bottom wall and provided with an open top, the front wall having a retaining bar on the exterior surface thereof and spaced from the open end of the container and forming a slot for extending 20 the cover of a match book thereunder, a match head cover on the front wall for covering the

heads of the matches in said match book, said match head cover being positioned adjacent the open top of said container and having a second slot therein adjacent the exterior surface of the container through which the match book cover may be extended, the rear wall of the container having a pressure bar extending thereacross and spaced from the rear wall to form a third slot and having a pressure block thereon projecting into said third slot for frictionally engaging the match book cover when extended over the top of the package and through said third slot for holding the same in position.

DALE D. HAYES.
